SUCTION CLEANER

William H. Kitto, Canton, Ohio, assignor to The
Hoover Company, North Canton, Ohio, a cor-
poration of Ohio

Application April 19, 1933, Serial No. 666,799

6 Claims. (Cl. 15—16)

The present invention relates in general to suction cleaners, and more particularly to a new and novel construction for cooling the driving motor in a suction cleaner. More specifically the invention comprises a construction by which cooling air is drawn through the cleaner motor into the suction-creating part of the suction cleaner for the purpose of cooling the motor, means being provided to prevent the return to the motor of dirt-laden air at the end of the cleaning operation.

It is an object of the present invention to provide a new and improved suction cleaner. It is a further object to provide new and improved motor-cooling means in a suction cleaner. Still another object is the provision, in a suction cleaner, of means to draw cooling air from the motor casing into the low suction area of the fan chamber for the purpose of cooling the motor. A still further object is a provision in a suction cleaner, of a construction which permits the suction-creating fan to draw cooling air through the motor, means being provided to prevent the flow of air from the fan chamber back into the motor casing. A still further object is the provision of means which automatically closes the cooling air passageway from the motor casing to the suction-creating means when the motor is dead. These and other more specific objects will appear upon reading the following specification and claims, and upon considering in connection therewith the attached drawing to which they relate.

Referring now to the drawing in which a preferred embodiment of the present invention is disclosed:

Figure 1 is a partial vertical cross section through a suction cleaner casing in which the present invention is embodied;

Figure 2 is a section upon the line 2—2 of Figure 1, and also upon the line 2—2 of Figure 3;

Figure 3 is an enlarged showing of the air passageway in the motor shaft at the point it emerges into the motor casing;

Figure 4 is a second embodiment of the present invention;

Figure 5 is a showing of a suction cleaner in which the present invention is embodied.

Suction cleaners today are provided with a high speed electric motor which drives a suction-creating fan which in turn effects the movement of cleaning air through the cleaner nozzle, the fan chamber, and into the dirt receptacle or dust bag. It is desirable that the electric motor be substantially completely incased in order that disturbed foreign matter will not lodge therein. Cooling

means are necessary for such motors and often take the form of a motor-cooling fan positioned in the motor casing. In the machine constructed in accordance with the present invention this additional fan has been eliminated and in its place use has been made of the suction-creating power of the main suction-creating fan of the cleaner. Means have been provided to overcome the undesirable effect of back pressure in the dust bag. If a direct opening were left from the fan chamber to the motor casing this back pressure would effect the movement of dirt-laden air from the fan chamber to the motor casing resulting in a deposition of undesirable foreign matter on the motor.

Referring again to the drawing a sufficient portion of a modern suction cleaner is illustrated to clearly illustrate the present invention. A motor casing 1 is secured at the rear of a fan chamber 2, the front wall 3 of the motor casing functioning as the rear wall of the fan chamber. A nozzle 4 is interiorly connected to the fan chamber 2 through an eye or inlet 5, and there is provided an exhaust outlet 6 on the fan chamber to which is attached a suitable dust bag 7.

Positioned within the motor casing 1 is the electric driving motor for the cleaner, the armature 8 being rotatably supported upon the shaft 9 which is itself carried at its forward end by a bearing 10 in the wall 3 and at its rear end by bearing 11. The motor field is indicated by the reference character 12 and is non-rotatably mounted within the casing 1.

The suction-creating fan 13 is carried by the motor shaft 9 forward of the wall 3 in the fan chamber 2, and upon the rotation of the motor this fan functions to draw cleaning air from the nozzle 4, through the fan chamber inlet 5 and exhaust it at high pressure through the exhaust outlet 6 and into dust bag 7. It is to be noted that bearing 10 is provided with a seal 10^a which cooperates to prevent the movement of dirt laden air through the bearing and into the motor casing.

In the construction according to the present invention the motor shaft 9 is counter-bored from its end within the fan chamber 2 to a point well within the motor casing 1, and is interiorly connected to both the interior of the motor casing and the fan chamber by radial openings 14 in the motor casing and 15 in the fan chamber, the latter openings being provided in the nut 16 which seats upon the end of the motor shaft to secure the fan 13 in place. It is to be noted that the openings 15 in the fan chamber are positioned at

the point of reduced pressure therein, that is, at the center of the suction-creating fan.

Within the motor casing seals 17, 17 are mounted on shaft 9 by springs 18, 18 and are held by these springs over the openings 14, 14. The force exerted by the springs is sufficient to hold the seals in place when the motor is not rotating but upon the motor reaching a certain speed centrifugal force acting upon the seals throws them outwardly against the spring force thereupon permitting unhindered access to the interior of the hollow motor shaft to air within the motor casing. An encircling cup or shield 19 encloses the seals 17, 17 in spaced relationship and functions to limit their outward radial movement under centrifugal force.

In the operation of this embodiment of the invention with the motor in the static condition seals 17, 17 are seated against the openings 14, 14 and the interior of the motor casing is sealed from the interior of the fan chamber. Upon the rotation of the motor, as when the cleaner is being used, upon reaching a predetermined speed centrifugal force throws the seals 17, 17 outwardly against the inward force exerted by the springs 18 and cooling air is drawn across the motor, having entered the casing at the opening 1^a in the rear thereof. This cooling air enters the hollow motor shaft through the openings 14, 14 and passes therethrough into the low pressure point of the fan chamber, entering that body through the openings 15, 15. So long as the motor continues to rotate at its normal operating speed this movement of cooling air continues. When the motor current is turned off, however, the motor speed is reduced and the spring force exerted by the springs 18, 18 becomes greater than centrifugal force and the seals are forced against the openings 14, 14. This last operation prevents the movement of dirt laden air from the fan chamber 2 under the back pressure force exerted by the air pressure existing in the dust bag 7.

Referring now to Figure 4, in particular, a slightly modified form of the present invention is disclosed which differs from the embodiment aforescribed in that the openings 15, 15 are positioned within the hub of the suction-creating fan 13 and are aligned with openings 20, 20 in the hub to permit the passage of air as in the first embodiment. This construction permits the use of a driving pulley 21 at the forward end of the motor shaft and makes possible the use of the invention in suction cleaners embodying positively driven agitating means. In other particulars this embodiment of the invention is the same as that aforescribed.

I claim:

1. In a suction cleaner, a fan chamber, a motor

casing, a motor including a rotatable shaft in said casing, said shaft being extended into said fan chamber and being hollow from a point in said casing to a point in said chamber, a fan carried by said shaft in said chamber, said shaft being open to said casing and to a low pressure point in said chamber, a seal closing the passageway between said chamber and said casing, and means normally holding said seal in closed position and adapted to move it to an open position upon the rotation of said shaft.

2. In a suction cleaner, a fan chamber, a motor casing, a motor including a rotatable shaft in said casing, said shaft being extended into said fan chamber and being hollow from a point in said casing to a point in said chamber, a fan carried by said shaft in said chamber, said shaft being interiorly connected by radial openings to said casing and chamber, a seal for one of said openings, a spring urging said seal into sealing relationship and opposing the centrifugal force exerted by said seal upon the rotation of said shaft, the strength of said spring being such that said seal moves to an open position upon said shaft reaching a predetermined speed of rotation.

3. In a suction cleaner, a dirt-laden-air passageway including a nozzle, a fan chamber, and an exhaust outlet; a fan in said fan chamber to create a reduced pressure in said nozzle to draw air therethru and exhaust it thru said outlet; a driving motor positioned adjacent said fan chamber, the shaft of said motor being extended into said chamber and carrying said fan; and a passageway connecting the interior of said motor to the nozzle side of said fan and dirt-laden-air passageway for the purpose of conveying cooling air from said motor.

4. The construction defined by the preceding claim characterized by the fact that said cooling-air passageway extends from said motor to the inlet of said fan chamber.

5. The construction recited in the second preceding claim characterized in that means are provided to automatically close said cooling air passageway when said motor rotates at less than a predetermined speed.

6. In a suction cleaner, a nozzle, a fan chamber, and an exhaust outlet, a fan in said fan chamber to create a reduced pressure in said nozzle to draw air therethru and exhaust it thru said outlet, a driving motor positioned adjacent said fan chamber, the shaft of said motor extended into said chamber and carrying said fan, said shaft being hollow from a point in said motor to a point of low pressure on the nozzle side of said fan chamber for the purpose of conveying cooling air from said motor into the dirt-laden air stream.

WILLIAM H. KITTO.
